UNITED STATES PATENT OFFICE.

CARL F. BRAUN, OF SAN FRANCISCO, CALIFORNIA.

TUBE-EXPANDING TOOL.

Application filed January 11, 1922. Serial No. 528,479.

To all whom it may concern:

Be it known that I, CARL F. BRAUN, a citizen of the United States, residing at the city and county of San Francisco, and State of California, have invented new and useful Improvements in Tube-Expanding Tools, of which the following is a specification.

This invention relates to a machine tool, 10 and particularly pertains to a tube expanding tool.

It is common practice to pass tubes through sheets and to thereafter expand the tubes into the openings through which they 15 pass, whereby a tight joint will be effected between the tube sheet and the tube.

In carrying out this operation it often happens that the tubes are ruptured and in some cases objectionably distended at points 20 along their length. Certain types of expanding tools also turn the ends of the tube over the outer face of the tube sheet. In either event, an objectionable structure is formed, as the tubes readily rupture, and when removed require that the tube be destroyed, and in some instances that the tube nest be dismantled. Certain types of expanding tools also act to exert inward pressure on the tubes, thus causing them to buckle between the plates.

With these objections in mind, it is the principal object of the present invention to provide a tube expanding tool which will quickly expand the tube within the opening through which it passes, at the same time insuring that the tube will not be buckled, will not be objectionably distended at points along its length, and that it will draw the metal of the tube in a manner to prevent crystallization or rupture of the wall.

The present invention contemplates the use of a rotary body member adapted to be inserted into the open end of a tube, said member carrying outwardly movable rollers which act to spin the metal of the tube wall and tend to draw the surplus metal outwardly, said rollers and body member being driven and operated by a centrally disposed tapered mandrel.

The invention is illustrated by way of example in the accompanying drawing, in which:

Fig. 1 is a view in elevation showing the 55 complete tool.

Fig. 2 is a view in transverse section through the tool as seen on the line 2—2 of Fig. 1.

Fig. 3 is a view in section and elevation showing the relative initial positions of the 60 parts of the tool.

Fig. 4 is a view similar to Fig. 3 showing the expanding action of the rollers.

Referring more particularly to the drawing, 10 indicates a body member of the expanding tool. This member is formed with a sleeve 11 enlarged at one end to provide a head 12. The sleeve substantially agrees in outer diameter with the inside diameter of a tube 13 which is to be expanded. The 65 enlarged head 12 is larger in diameter than the outside diameter of the tube, thus permitting an annular recess 14 to be formed around the end of the head abutting against a tube sheet 15. The width of this recess 70 is sufficient to accommodate surplus metal of the tube wall in a manner which will be hereinafter described.

Longitudinally extending slots 16 are formed through the sleeve 11. These slots 80 are disposed at a slight inclination to the longitudinal center of the body member 10 and receive expanding rollers 17. As shown in Fig. 2 of the drawing, three expanding rollers are provided. These rollers seat 85 within the slots 16, and due to the fact that the opposite side walls of the slots are arcuate as indicated at 18 the rollers will remain within the slots, although they may have considerable lateral play. The rollers are 90 frusto-conical in shape, having a slight taper. The bases of the rollers are disposed near the end of the sleeve portion 11, while the reduced ends of the rollers extend into continuations of the slots 16, which are 95 formed through the head 12. A removable collar 19 is secured against the outer end face of the head by screws 20. This collar prevents longitudinal displacement of the rollers and holds them within the slots. In 100 order to obtain the best results the length of the rollers extending along the sleeve beyond the shoulder face of the head 12 agrees in dimension with the thickness of the tube sheet 15. This will cause the outer end of 105 the rollers to terminate near the line of the inner face of the tube sheets. In any event it is not desirable to extend the ends of the rollers beyond the inner face of the tube sheet, for then the expanding action of the 110

rollers would probably distend the unsupported wall of the tube near the sheet.

Expanding action is brought about by a tapered mandrel 21, the taper of which mandrel is substantially twice that of the roller taper, thus insuring that the outer faces of the rollers will lie parallel with the central axis of the mandrel when the mandrel is forced into the central opening of the body member 10 and into engagement with the various rollers.

In operation of the present invention the assembled tool is inserted into the open mouth of a tube, it being understood that the tube has previously been positioned through its tube sheet. It is desirable that the end of the tube shall lie flush with the outer face of the tube sheet, as will be hereinafter understood. The tapered mandrel 20 may then be inserted into the opening 22 through the body and brought into a wedging position against the rollers 17. At this time it is to be understood that the shoulder face of the tool body is resting against the outer face of the tube sheet, as shown in Fig. 3. Suitable means may be provided to rotate the mandrel in a clockwise direction. For convenience this means may be a portable electric or air motor fitted with a chuck 25 to grip the cylindrical end 23 of the mandrel. As the mandrel rotates in a clockwise direction, it will frictionally engage the rollers 17 and will have a tendency to cause the tool body to rotate in unison therewith, at the same time the friction of the mandrel on the rollers causing them to roll in a counter direction to that of the mandrel and the tool body.

Attention is again directed to the fact that the rollers 17 are disposed at angles to the longitudinal axis of the tool and it is to be further noted that the smaller ends of the rollers will be in advance when the tool rotates in a clockwise direction. The counter-clockwise rotation of the rollers at this angle will tend to work the surplus metal of the tube outwardly as the tool operates. This action will not be appreciable until after the rollers have completely expanded the tube into the tube sheet opening. Then the rollers will tend to spin the metal wall of the tube and lap the surplus metal toward the outer end of the tube as shown in Fig. 4. This surplus metal will extend into the recess 14 of the head 12 and in the event that continued pressure is delivered to the mandrel while rotating it may be possible to lap sufficient metal out to crimp the end of the tube against the tube sheet. This operation is, however, not necessary in the present instance, as the expanding rollers will insure that a tight joint will be made between the tubes and their sheets, without danger of rupturing the tube walls or otherwise weakening them. In performing the

expanding operation it is only necessary to spin the tool for a few turns in order to sufficiently expand the tube. The workman slightly withdraws the tool at intervals during operation, and when he notices the end of the tube projecting from the outer face of the tube sheet he is thus advised that the joint is sufficiently tight, and that his additional pressure is acting to force the metal longitudinally of the tube as well as expand the tube. The action of the tool also tends to draw the tubes lengthwise, thus straightening them between the tube sheets and placing them under a desirable tension.

It will thus be seen that the device here disclosed provides a simple and effective means for rapidly expanding tubes into their sheets in a manner to insure against rupture or breaking of the tubes, and to permit the individual tubes to be readily withdrawn from their sheets.

While I have shown the preferred form of my invention, as now known to me, it will be understood that various changes might be made in the combination, construction and arrangement of parts by those skilled in the art, without departing from the spirit of the invention, as claimed.

Having thus described my invention, what I claim and desire to secure by Letters Patent is:

1. A tube expanding tool comprising means for acting to simultaneously expand the wall of a tube into an opening in a tube sheet and draw the metal of the tube longitudinally through the opening in the tube sheet, said means including a member abutting against the face of the tube sheet and having an annular recess in its abutting face concentric with the tube sheet to receive the drawn out metal at the end of the tube.
2. A tool for expanding a tube into an opening formed in a tube sheet, comprising a rotatable member adapted to be inserted into the end of the tube and having an enlarged head adapted to abut against the outer face of the tube sheet, tube expanding elements carried by said rotatable member and moving therewith, and means for imparting a rotary motion to the rotatable member while simultaneously exerting a counter-rotary motion of the expanding elements and causing them to move outwardly in unison, whereby to expand the tube outwardly and spin the wall of the tube forwardly longitudinally of the axis of the expanded wall, the said head having an annular groove in its abutting face concentric with the tube to receive the end of the tube drawn through the opening.
3. A tool for expanding a tube into an opening formed in a tube sheet, comprising a tubular member extending into the tube and having an enlarged head at one end thereof adapted to abut against the outer

face of the tube sheet, a plurality of frustoconical rollers extending lengthwise of the sleeve and arranged for movement outwardly against the inner wall of the tube, 5 a tapered mandrel extending into the tubular body member and engaging the inner surfaces of the rollers whereby the rollers may be simultaneously moved outwardly and the rollers and body member frictionally driven in opposite directions, and 10 means whereby the individual rotation of the rollers will cause the metal of the expanding wall to be drawn toward the end of the tube, the said head having a recess in its abutting face concentric with the 15 opening in the tube sheet to permit slight projection of the tube beyond the outer face of the tube sheet without contact with said

member or its head and thereby prevent upsetting of the end of the tube. 20

4. A tube expanding tool comprising means including elements for expanding and spinning the metal at the end of a tube to provide a tight joint between the end of the tube and an opening formed in a tube 25 sheet and draw the metal of the tube slightly beyond the outer face of the tube sheet, said means including a hollow head provided with a shallow recess in its inner face adjacent its inner wall to receive the 30 projecting end of the tube without contact of the tube with the walls of said recess whereby to prevent accidental upsetting or rupture of the projected end of the tube.

CARL F. BRAUN.
